UNITED STATES PATENT OFFICE.

WILLIAM L. CHANDLER, OF MISHAWAKA, INDIANA, ASSIGNOR TO NATIONAL SAFETY COUNCIL, OF CHICAGO, ILLINOIS, AN ASSOCIATION.

DESIGN FOR A DANGER-SIGN.

51,631.

Specification for Design.

Patented Jan. 1, 1918.

Application filed December 13, 1916. Serial No. 136,796. Term of patent 14 years.

To all whom it may concern:

Be it known that I, WILLIAM L. CHANDLER, a citizen of the United States, residing at Mishawaka, in the county of St. Joseph, State of Indiana, have invented a new, original, and ornamental Design for a Danger-Sign, of which the following is a specification, reference being had to the accompanying drawing, forming part thereof.

The figure is a plan view of the danger sign showing my design.

I claim:

The ornamental design for a danger sign as shown.

W. L. CHANDLER.
